Macleay Edmond Lawrie, 18 Wellington St., Alberton,
South Australia, Australia
Filed Oct. 24, 1951, Ser. No. 147,306
Claims priority, application Australia Oct. 26, 1960
10 Claims. (Cl. 114—16)

This invention relates to submarines.

Already known are underwater diving craft or submarines which are provided with motors operating from batteries or the like and which are enclosed so that a person can be accommodated in the hull of the submarine and can maneuver the same underwater.

It has also been proposed to use open vanes or paravanes on which a person sits or lies, which are towed through the water and permit the person to dive by changing the angle of control members.

With the known self-propelled craft there is considerable difficulty in navigating the craft and establishing location as for example, when checking the habits of fish or the like. Furthermore the known craft are of very high cost, and for average purposes are not economical.

On the other hand the open type of towed unit, or the unit of the type employing a miniature motor which tows a skin diver, is subject to the dual objection that firstly the diver is subjected to the possibility of attack by sharks or other large fish or jelly fish, and secondly that the diver is subject to wide variations in pressure and temperature which can in some circumstances prove dangerous.

The main object of this invention is to provide a submarine which is simple in design and low in cost and yet which is substantially safe. The purposes to which such a submarine may be placed are of course many and varied, and for example, include the study of fish habits and population, marine vegetable growth, sea floor topography, engineering installations and the like.

When specialized study is required, a problem frequently exists in that the specialist performing the study is not an experienced diver, and one of the objects of this invention is to provide inexpensive means whereby a specialist may make his study without the need for training as a diver, and without being subjected to the various dangers encountered in diving.

In its simplest form the invention may be said to be embodied by a submarine which comprises a hull, tow-rope engagement means on the outside of the hull, at least one transversely disposed vane shaft, sealably journaled to bearings in the hull and disposed rearwardly of said tow-rope engagement means, a vane on said shaft or shafts, hand operable vane control means within the hull coupled to said shaft or shafts, a transparent observation panel in the hull, a waterproof hatch on the hull, and locking means between the waterproof hatch and the hull.

Embodiments of the invention are described hereinafter in some detail with reference to the accompanying drawings in which:

FIG. 1 is a side elevation of a first embodiment of a submarine being towed,

FIG. 2 is a plan view of the submarine of FIG. 1 on a somewhat larger scale,

FIG. 3 is an elevational section of a submarine according to a second embodiment,

FIG. 4 is a section through lines 4—4 of FIG. 3,

FIG. 5 is a section through lines 5—5 of FIG. 3,

FIG. 6 is a section through lines 6—6 of FIG. 3, and

FIG. 7 is a section through lines 7—7 of FIG. 3.

Referring firstly to the embodiment of FIGS. 1 and 2, a submarine 10 consists of a hull 11, the hull 11 includ-

ing an annular transparent panel 12 between a lower cup-like portion 13 and a closure hatch 14.

The closure hatch 14 is retained in position by an outwardly disposed clamping nut 15, and also by inwardly disposed clamping means which are described in some detail with reference to the second embodiment of FIGS. 3, 4, 5, 6 and 7.

Disposed forwardly of the medial transverse axis 17 is a pair of lugs 18 which, together with pins 19, constitute tow-rope engagement means which engage the tow-rope 20. The lugs 18 are disposed symmetrically about a longitudinal center line of the submarine 10. The tow-rope 20 is short in length and its two ends are engaged on the pins 19, but intermediate its ends it engages the loop 21 of a main towing cable 22 which is secured to a towing vessel (not shown).

A pair of transversely disposed vane shafts 25 are journaled and sealably engaged in bearings 26 in the hull 11, and each vane shaft 25 carries on it a vane 27 which includes a forwardly disposed portion 28 which is half the area of the rearwardly disposed portion 29 so that the vanes 27 are at least partly balanced against the pressure tending to rotate them, whereby they are more easily controlled from within the submarine 10.

25 A telephone cable 31 passes through a waterproof fitting 32 into the submarine 10 so that a telephone is readily usable and retains communication between the towing vessel (not shown) and the submarine 10.

The embodiment of FIGS. 3, 4, 5, 6 and 7 illustrates 30 a submarine of similar general design to that of the embodiment of FIGS. 1 and 2 in that the submarine is generally circular in form and comprises a hull 11, an annular transparent panel 12, a lower cup-like portion 13, a closure hatch 14, and an outer clamping nut 15. As 35 in the case of FIGS. 1 and 2, the tow-rope engagement means comprises a pair of lugs 18 one on each side of the longitudinal center line of the hull 11, and these lugs 18 are associated with pins 19 which engage the ends of a tow-rope 20 (see FIG. 6).

40 In the passage of a submarine 10 through the water there is always a danger of the vanes 27 striking an obstruction such as a rock upstanding from the sea bed, and it is important that damage should be reduced to a minimum. In order to so reduce the damage, the second embodiment utilizes a small diameter intermediate shaft 35 which is of low cost and which is secured at one end to that portion of the vane shaft 25 which is journaled in the bearing 26 in the hull 11, and the intermediate shaft 35 is secured at the other end to the portion of the vane shaft 25 to which the vane 27 is secured.

In the case of the small and simple submarine illustrated in FIGS. 1 and 2, the control means for controlling the angular variation of the vane shafts 25 simply comprises a lever on each of the shafts 25 within the hull 11, this however not being shown in the drawings.

However in this embodiment of FIGS. 3, 4, 5, 6 and 7, the shaft 25 extends inwardly within the hull 11 and terminates in a chain wheel 37 which is linked by 60 a chain 38 to a small sprocket 39 on a short control shaft 40, the control shaft 40 being keyed to a hand wheel 41 and being journaled to a bearing 42 on an upstanding post 43 secured to the floor 44 of the hull 11. There are two such arrangements, one for each of the vane shafts 25, so that each vane shaft 25 is 65 separately controlled by a handwheel 41 so that the submarine can be maintained in a vertical position during its travel through the water.

FIG. 3 indicates the means by which the annular transparent panel 12 is secured to the hull 11, the transparent panel 12 being disposed between a ring 47 and an upper ring 48, the two rings being clamped together by a se-

ries of tie bolts 49, and the annular transparent panel 12 being sealed along its top and bottom edges by means of the rubber gaskets 50, and being reinforced by contiguity with the bolts 49.

The closure hatch 14 is clamped to a bow member 53 by means of the hinged clamp nut 54, the handle 55 of which may be unscrewed to facilitate slackening of the nut 54 in event of it being tightly engaged on the thread of the clamping bolt 56. The outer clamping nut 15 engages a sealing washer 57, and with the arrangement shown the closure hatch 14 can be released either from inside or from outside the submarine.

With the submarine shown in the embodiment of FIGS. 1 and 2, the only manner in which directional control can be effected is by tilting the submarine by differential control of the vanes 27 which tends to cause the submarine to yaw and follow a circular path around the towing vessel. However, for some purposes it is desirable that limited directional control be effected from within the submarine 10, and to achieve this a rudder 60 is secured to the outside of the hull 11. The hull 11 has an upper rudder support post 61 projecting rearwardly therefrom and a lower support tube 62 parallel to the upper post 61, the tube 62 being closed at its outer end. The tube 62 however, has a sealed upper bearing 63 in alignment with the closed lower bearing 64, and the rudder shaft 65 is rotational within the bearings 63 and 64 and sealably engaged by them. A comparatively light weight rudder pin 66 is secured for rotation with the rudder shaft 65 at its lower end and is journaled at its upper end in the post 61. The rudder pin 66 passes through a rudder housing 67 which is tubular in form, and the pin 66 is secured to the housing 67. The rudder 60 has a forwardly projecting portion 68 which is half the area of the rearwardly projecting portion 69 so that the rudder 60 is at least partly balanced by the thrust of water upon it. A sprocket 71 is keyed to the rudder shaft 65 and linked to a rudder control bar 72 by the roller chain 73. In this manner an operator sitting on the seat 74 with his feet on the rudder control bar 72 has directional control over the submarine 10.

In the event of the submarine 10 being towed against an obstruction, it is desirable to have a ready release of the rope, and this arrangement is shown in FIGS. 3 and 6. A kick bar 78 is hinged about a hinge pin 79 within the hull 11, and when displaced from the position shown to the position shown dotted in FIG. 3, the kick bar allows the spring-loaded pin 80 to travel inwardly under the pressure exerted by the spring 81 until its head 82 strikes the plate 83 welded to the hull 11. At least one kick bar is utilized, and preferably two, so that the submarine can be completely freed from the tow-rope 20.

In order to maintain communication, a telephone 86 is connected by means of a cable 31 which passes through a screw threaded sealing fitting 32 (see FIG. 7) The screw-threaded sealing fitting 32 includes a pair of cap nuts 89 which sealably clamp rubber O rings 90 into firm engagement with the cable 31 and with the fitting 32.

In order to enable the submarine 10 to be flooded, a gate valve 92 is positioned in its floor 44, and a second gate valve 93 is positioned in its closure hatch 14, the second gate valve 93 providing means for air entry if this is desired.

The submarine preferably carries aqualung equipment or other safety breathing apparatus to permit the occupant to safely leave the submarine in the case of accident, or for other purposes, and a CO₂ absorption unit is preferably enclosed in the hull. With this arrangement an operator can be submerged for about one hour without need to replace air in the submarine.

Also the hull preferably tows a marker buoy which can also serve as an air reservoir in that the buoy can

be coupled to the hull by a flexible hose through which air can be supplied.

In the event of an accident this marker buoy would allow quick pick-up of the hull but for all normal purposes the hull would float because of its buoyancy, immediately after it is released from the tow rope and forward motion has ceased.

It will be realized that when using a towed hull which is completely sealed, the occupant or occupants of the submarine can be comfortably housed in a dry condition and can have required quantities of fresh air fed to them either from the surface or by air conditioners or purifiers within the hull.

As the hull is towed by a surface vessel, the operators 15 of the hull are relieved of the necessity to navigate and are thus free to give their full attention to examination of the ocean bottom and other tasks set for such crafts.

The craft can be fitted with a scoop by means of which it can pick up pearl shells or other objects by simply 20 forcing the craft down to bring the scoop into action, and if the scoop is formed of mesh, only the objects picked up will remain in same, the water flowing straight through.

Closed television or a similar system could be used between the submarine and the towing vessel to enable 25 remote vision, and the vanes on the submarine may be operated by remote control from the towing vessel.

A device may be incorporated whereby the operator can drop smaller marker buoys or release marking oil when desired.

External ballast may be carried if necessary and jettisoned by the operator if required. Likewise the scoop 30 may be jettisoned in the event of rocks or other matter affecting the buoyancy or stability.

A unit so constructed will have the very great advantage that it could patrol or examine large areas of the ocean, while the occupants are free to concentrate on the collection of data or samples or the like without having to plot a course and generally navigate an underwater craft with its attendant problems and difficulties.

40 What I claim is:

1. A submarine comprising a hull having a medial transverse axis, tow-rope engagement means on the outside of the hull disposed forwardly and upwardly of the medial transverse axis of the hull, a single pair of transversely disposed vane shafts sealably journaled in bearings in the hull and disposed rearwardly and downwardly of said medial axis, a vane on each of said shafts, hand operable vane control means within the hull coupled to each of said shafts, a transparent observation panel in the hull, a waterproof hatch on the hull, and locking means between the waterproof hatch and the hull.

2. A submarine comprising a hull having a medial transverse axis, tow-rope engagement means on the outside of the hull disposed forwardly and upwardly of the medial transverse axis of the hull, a single pair of transversely disposed vane shafts sealably journaled in bearings in the hull and disposed rearwardly and downwardly of said medial axis, a vane on each of said shafts, hand operable vane control means within the hull coupled to each of said shafts, an annular transparent observation panel extending around the hull, a waterproof hatch on the hull, and locking means between the waterproof hatch and the hull.

3. A submarine comprising a hull having a medial transverse axis, tow-rope engagement means on the outside of the hull disposed forwardly and upwardly of the medial transverse axis of the hull, a single pair of transversely disposed vane shafts sealably journaled in bearings in the hull and disposed rearwardly and downwardly of said medial axis, a vane on each of said shafts, hand operable vane control means within the hull coupled to each of said shafts, an annular transparent observation panel sealably clamped between two axially spaced rings and extending around the hull, a waterproof hatch on 65 one of said rings and disposed above the annular trans-

parent observation panel, and a clamping bolt between the waterproof hatch and the hull, an outer clamping nut on the clamping bolt releasable from without the hull, and an inner clamping nut on the clamping bolt releasable from within the hull.

4. A submarine comprising a hull having a medial transverse axis, tow-rope engagement pins on the outside of the hull disposed forwardly and upwardly of the medial transverse axis of the hull, tow-rope pin release means within the hull operable to withdraw the tow-rope pins to a tow-rope disengagement position, a single pair of transversely disposed vane shafts sealably journaled in bearings in the hull and disposed rearwardly and downwardly of said medial axis, a vane on each of said shafts, hand operable vane control means within the hull coupled to each of said shafts, a transparent observation panel in the hull, a waterproof hatch on the hull, and locking means between the waterproof hatch and the hull.

5. A submarine comprising a hull having a medial transverse axis, tow-rope engagement means on the outside of the hull disposed forwardly and upwardly of the medial transverse axis of the hull, a single pair of transversely disposed vane shafts sealably journaled in bearings in the hull and disposed rearward and downwardly of said medial axis, a vane on each of said shafts, hand operable vane control means within the hull independently coupled to each of said shafts, a rudder on the hull, rudder control means in the hull, a transparent observation panel in the hull, a waterproof hatch on the hull, and locking means between the waterproof hatch and the hull.

6. A submarine comprising a hull having a medial transverse axis, a pair of aligned withdrawable spring loaded tow-rope pins sealably engaging and axially slideable through the walls of the hull and disposed forwardly and upwardly of the medial transverse axis thereof, a pair of hinged kick bars engaging the pins thereby retaining the pins in a tow-rope engagement position, said kick bars being movable about pivotal mountings to disengage said pins whereupon said pins are urged to slide axially to a tow-rope disengagement position, a single pair of aligned transversely disposed vane shafts sealably journaled in bearings in the hull, said vane shafts being disposed rearwardly of said tow-rope pins, a pair of vanes one on each vane shaft, hand operable vane control means within the hull independently coupled to each said vane shaft, an annular transparent panel sealably clamped between two axially spaced rings and extending around the hull, a waterproof hatch on the hull, and locking means between the waterproof hatch and the hull.

7. A submarine comprising a circular hull, withdrawable spring loaded tow-rope engagement pins on the outside of the hull, a pair of aligned transversely disposed vane shafts sealably journaled in bearings in the hull, said vane shafts being disposed rearwardly of said tow-rope pins, a pair of vanes one on each vane shaft, a pair of chain sprockets one on the inner end of the inner portion of each vane shaft, a post upstanding from the floor of the hull, a pair of aligned control shafts journaled in bearings on the post, a hand wheel and a chain sprocket on each control shaft, a pair of roller chains coupling corresponding sprockets whereby each vane is independently controllable by a hand wheel, an upper rudder post extending rearwardly of the hull, a lower rudder tube parallel to but spaced from the upper rudder post, a rudder shaft journaled at its upper end in the rudder post and sealably journaled at its lower end in the rudder tube, a rudder on the rudder shaft, a sprocket on the rudder shaft, a hinged rudder control bar, a chain between the rudder shaft sprocket and the rudder control bar, an annular transparent panel sealably clamped between two axially spaced rings and extending around the hull, a bow member engaging at its ends one of said rings, a closure hatch sealably engaging the outer of said rings, a clamping bolt between the bow member and the closure hatch, and clamping bolt release means operable either from within or from without the hull.

8. A submarine comprising a circular hull, withdrawable spring loaded tow-rope engagement pins on the outside of the hull, a pair of aligned transversely disposed vane shafts sealably journaled in bearings in the hull, said vane shafts being disposed rearwardly of said tow-

6
rope pins, a pair of vanes one on each vane shaft, hand operable vane control means within the hull coupled to the shaft, an upper rudder post extending rearwardly of the hull, a lower rudder tube parallel to but spaced from the upper rudder post, a rudder shaft journaled at its upper end in the rudder post and sealably journaled at its lower end in the rudder tube, a rudder on the rudder shaft, a sprocket on the rudder shaft, rudder control means, a chain between the rudder shaft sprocket and the rudder control means, an annular transparent panel sealably clamped between two axially spaced rings and extending around the hull, a waterproof hatch on the hull, and locking means between the waterproof hatch and the hull.

9. A submarine comprising a circular hull, withdrawable spring loaded tow-rope engagement pins on the outside of the hull, a pair of aligned transversely disposed vane shafts sealably journaled in bearings in the hull, said vane shafts being disposed rearwardly of said tow-rope pins, a pair of vanes one on each vane shaft, hand operable vane control means within the hull coupled to the shaft, an annular transparent panel sealably clamped between two axially spaced rings and extending around the hull, a bow member engaging at its ends one of said rings, a closure hatch sealably engaging the outer of said rings, a clamping bolt between the bow member and the closure hatch, an outer clamping nut on the clamping bolt reacting against the closure hatch, a hinged clamp nut reacting against the bow member, a handle on the hinged clamp nut operable to open same, and at least one valve in the wall of the hull.

10. A submarine comprising a circular hull, a pair of aligned withdrawable spring loaded tow-rope pins axially slideable through the walls of the hull and disposed forwardly of its medial transverse axis, a pair of hinged kick bars engaging the pins thereby retaining the pins in a tow-rope engagement position, said kick bars being movable about pivotal mountings to disengage said pins whereupon said pins are urged to slide axially to a tow-rope disengagement position, a pair of aligned transversely disposed vane shafts sealably journaled in bearings in the hull, said vane shafts being disposed rearwardly of said tow-rope pins, each vane shaft being in two aligned positions joined by a replaceable intermediate shaft of smaller diameter, a pair of vanes one on the outer portion of each vane shaft, a pair of chain sprockets one on the inner end of the inner portion of each vane shaft, a post upstanding from the floor of the hull, a pair of aligned control shafts journaled to bearings on the post, a hand wheel and a chain sprocket on each control shaft, a pair of roller chains coupling corresponding sprockets whereby each vane is independently controllable by a hand wheel, an upper rudder post extending rearwardly of the hull, a lower rudder tube parallel to but spaced from the upper rudder post, a rudder shaft journaled at its upper end in the rudder post and sealably journaled at its lower end in the rudder tube, a rudder on the rudder shaft, a sprocket on the rudder shaft, a hinged rudder control bar, a chain between the rudder shaft sprocket and the rudder control bar, an annular transparent panel sealably clamped between two axially spaced rings and extending around the hull, a bow member engaging at its ends one of said rings, a closure hatch sealably engaging the outer of said rings, a clamping bolt between the bow member and the closure hatch, an outer clamping nut on the clamping bolt reacting against the closure hatch, a hinged clamp nut reacting against the bow member, a handle on the hinged clamp nut operable to open same, and at least one valve in the wall of the hull.
